(57) CLAIM

The ornamental design for a wok set as shown and described.

DESCRIPTION

FIG. 1 is a top perspective view of the wok set showing my new design.

FIG. 2 is a front view thereof.

FIG. 3 is a side view thereof.

FIG. 4 is a front view thereof.

FIG. 5 is another side view thereof.

FIG. 6 is a top view thereof.

FIG. 7 is a bottom view thereof.

FIG. 8 is a top perspective exploded view thereof; and,

FIG. 9 is a bottom perspective exploded view thereof.

The broken lines in the drawings illustrate portions of the wok set which form no part of the claimed design.
